(57) **CLAIM**

The ornamental design for a tele-psychiatric cart, as shown and described.

DESCRIPTION

FIG. 1 is a perspective view of a tele-psychiatric cart showing my new design;

FIG. 2 is a front view thereof;

FIG. 3 is a back view thereof;

FIG. 4 is a side view thereof;

FIG. 5 is a top view thereof; and,

FIG. 6 is a bottom view thereof.

In the drawings, the broken lines depict unclaimed subject matter only and form no part of the claimed design.

1 Claim, 4 Drawing Sheets
